Term of patent 14 years

Int. Cl. D6—03

U.S. Cl. D6—175

FIG. 1

FIG. 2

FIG.3

FIG.4

FIG.5

FIG. 1 is a perspective view of my new design;
 FIG. 2 is a side elevation view of the design of FIG. 1, the sides being identical;
 FIG. 3 is a top plan view of the design;
 FIG. 4 is a bottom view of the design; and
 FIG. 5 is an end elevation view of the design, the ends being identical.

The design is characterized by a pair of thin V-shaped leg supports in combination with a narrow brace member extending laterally therebetween with said combination being attached inwardly of the peripheral edge of the table top and contiguous with the undersurface thereof, all as best illustrated in FIGS. 1 and 2.

This application is a continuation-in-part of my co-pending application Ser. No. 169,586, filed Aug. 5, 1971, and now abandoned.

I claim:

The ornamental design for a toy coffee table or similar article, as shown and described.
